CONTAINER SEAL

Robert T. Thompson, Palatine, Ill.

Application February 24, 1956, Serial No. 567,492

13 Claims. (Cl. 220—27)

The present invention relates to container sealing and access means, and more particularly relates to a new and improved container sealing device and means providing for simplified and more convenient and improved opening of a container such as a conventional can.

Still more particularly, the present invention is directed to a container with sealing means therefor providing convenient and easy access means for discharging the contents of the can without need or use of any special tools such as keys or cutting type can openers or other special devices. By the present invention a container may be opened merely by exerting manual pulling force on the sealing device.

Additionally, containers and sealing devices incorporating the principles of this invention may be opened in any number of ways such as removal of the entire container top, removal of a majority of the container top, or removal of only such parts of the container top as are necessary for access to the contents of the can. For example, in a beverage can or a can containing other liquids, it may be highly desirable merely to provide a pair of apertures in the can, one of which is for pouring and the other of which is for venting. With the same type of contents, it may be desired to open but a single aperture in the can and equip the can with a self contained straw, an end of which will pop when the can seal is removed, permitting access to the can. These and many additional features and advantages obtain through the utilization of this invention.

By the present invention any part of the can top or the entire can top or parts of the can top can be removed or exposed or apertures in the can top may be exposed providing access to the contents of the can by sealing the can top or any part or parts thereof or any apertures therein with a seal formed from spirally wound elongated length of wire, the convolutions of which are sealed together and the entire spiral of which is sealed to the can top or over the parts to be removed or over an aperture therein or between the can top and the side walls of the can by a material of the sufficiently low tensile strength to be broken under ordinary manual force but of a sufficiently high tensile strength to withstand forces developed from fluid pressures within the can.

Thus, it is an important object, feature and advantage of the present invention to provide a new and improved container sealing means and access providing means.

Another object of the present invention is to provide a new and improved container seal readily removable for access to the container without supplementary tools etc. and merely through the use of manual pulling force.

Still another object of the present invention is to provide a new and improved container seal of spirally wound elongated wire, the convolutions of which are sealed together and to the container at the top thereof.

Yet another object of the present invention is to provide a new and improved container seal having one or

2

more spirally wound portions thereof overlying an aperture or a knockout in the container top, said seal arranged substantially in one plane with its convolutions wound about a fixed center and continually receding from said center, and said seal secured to the container top, yet readily removable therefrom by manual force breaking the sealing means and unwinding the convolutions until the aperture is uncovered or the knockout withdraws from the container top with the unwound convolutions.

10 There are numerous other objects, features and advantages to the present invention and many of these will readily appear from the following detailed description of the present invention and embodiments thereof, from the claims, and from the accompanying drawings in which each and every detail shown is fully and completely disclosed as a part of this specification, in which like reference numerals refer to like parts, and in which:

Figure 1 is a plan illustration of a spirally wound wire sealing member embodying the principles of this invention;

Figure 2 is a plan view of a container sealed in accordance with the principles of this invention;

Figure 3 is a fragmental sectional view of the container of Figure 2 viewed as taken substantially along the line III—III of Figure 2; and

Figure 4 is a fragmental sectional view like Figure 3 but illustrating another form of this invention;

Figure 5 is a fragmental sectional view of still another form of the invention and is like Figure 3;

Figure 6 is a full sectional view of a container having still another form of sealing thereof in accordance with the principles of this invention;

Figure 7 is a fragmental sectional view of a container having still another form of sealing thereof in accordance with this invention; and

Figure 8 is a fragmental sectional view of a container having still another form of sealing thereof in accordance with the principles of this invention.

One form of sealing a container in accordance with the principles of the invention employs the utilization of a spirally wound wire such as is illustrated in Figure 1. The wire itself may be of any desired composition so long as it is utilizable for the purposes of this invention. One typical example of such a wire may be a tinned copper wire that is solderable either through direct application of heat or through radio frequency heating and soldering etc. When applying soldering to hold the convolutions together, the solder also forms a seal between the adjacent convolutions so that the adjacent convolutions are actually sealed against fluid or other material flow therebetween.

As illustrated in Figure 1, the closure seal 10 has a series of convolutions 11—11 extending entirely to the center of a spiral, as at 12, and all of the convolutions are sealed together through the medium of a securing means such as solder. The particular solder employed may be of any number of desired compositions. Here it is preferred that the lead and tin proportions thereof be varied to an optimum condition of tensile strength permitting manual force breaking of the seal between adjacent convolutions and yet having sufficient strength to withstand fluid pressures from within a container such as a beverage container wherein the gas pressures rise to relatively high levels. In the form of spiral wire sealing member shown in Figure 1 there has been provided a single spiral having its outside loop lead to a finger loop 13 at the free end of the wire thereby providing means accommodating exerting manual force on the spiral to strip the convolutions apart by unwinding. This finger loop is formed by doubling over an end of the wire, as at 14, and soldering the looped over end to an adjacent portion of the wire.

70

This form of single spiral and finger loop sealing member may be employed with any of the containers illustrated in Figures 2 through 8 but achieves maximum utilization in the form of can sealing illustrated in Figure 6 described in detail hereinafter.

In the form of invention illustrated in Figures 2 and 3, the elongated wire is formed from a pair of flat spirals 15-15 at opposite ends of a wire with an intermediate linking portion 16. These spirals 15-15 overlie punched apertures 17'-17', respectively, in a can top 17 forming a part of a conventional can 18.

The top 17 of this can 18 is sealed to the cylindrical side walls 19 in a conventional manner by having a roll formed bead 20 therebetween. This bead 20, as is conventional in can manufacture, has a rolled over edge on the upper end of the side walls 19 and a double rolled edge at the outer periphery of the can tops 17 interlocking with the rolled edge on the side walls 19.

The particular form of the present invention illustrated in Figures 2 and 3 is especially adaptable to cans containing beverages and other liquids inasmuch as it provides a double aperture opening in the can for access to the liquids, thereby providing a pouring aperture and a venting aperture. While both of the apertures are shown as being substantially identical, it will be readily understood that this is merely by way of convenience of illustration description and that the apertures may have any desired configuration thus adapted to pouring and venting as desired.

The spiral seals 15-15 overlie the apertures 17'-17' and are soldered or secured otherwise as desired to the top 17 of the can by either direct heat soldering or radio frequency soldering etc. as is found most expedient. Again, the solder employed will have an optimum tensile strength sufficiently low to permit manual removal of the spirals and yet withstand the force of pressures from within the can.

Removal of the sealing spirals 15-15 is most easily and conveniently effected for access to the contents of the container merely by pulling the finger tab portion 16 of the wire forming the double spirals thereby unwinding the spirals until a sufficient number of the convolutions thereof have been removed from the can top 17 to effectively break the spirals loose from the can top thereby exposing the apertures 17' and permitting access to the contents of the container.

While the flat spirals 15-15 of this form of the invention are shown as fully overlying the apertures and being fixed onto the upper outer surface of the can top 17, it will also be understood that the present invention is equally effective should the spirals be of lesser diameter than that shown so that they will set onto the bosses 21-21 converging inwardly about the apertures 17'-17'. Such a correlation between the spiral seals and the bossed apertures provides the additional advantages of a smooth top on the can as well as prelocating the spirals with the apertures for high speed production and radio frequency soldering or sealing.

In the form of the invention illustrated in Figure 4 the can 22 is identical with the can 18 inasmuch as its top 23 and side walls 24 are identical with the corresponding parts 17 and 19 of the can 18 and they are sealed together in a roll formed seal 25 identical with the seal 20. The apertures 26-26 in the can top 23, however, are sealed by a double spiral conically formed seal 27-27 interconnected by a finger pull tab 28. These conical spiral seals 27-27 are otherwise the same as the flat spiral seals 15-15 in that adjacent convolutions thereof are sealed together and the outer convolutions are sealed onto the flange lips or bosses 29-29 of the apertures 26-26. This form of seal provides still additional pressure resisting strength to withstand fluid pressures from within the can in the event that the beverage within the can is a carbonated beverage or the fluid within the can is a fluid having a volatility of a

proper level to provide a relatively high fluid pressure within the can.

The flat double spiral form of seal is also employed in the embodiment of the invention illustrated in Figure 5 on a container 30 very similar to the containers 18 and 22 in that the sides 31 may be identical with the sides 19 and 24 and further with a top 32 roll formed seal as at 33 with the sides 31 in the same manner that the tops 17 and 23 are roll formed sealed as at 20 and 25 to the sides 19 and 24, respectively. In this form of the invention, however, the apertures in the can have knockouts 34-34 therein by providing the can top with a pair of cuts 35-35 which are annular in form, or have any other desired configuration, but which do not extend entirely through the thickness of the can top 32. Instead, the cuts 35-35, while peripherally complete, extend inwardly from the outer surface of the can top 32 to a plane closely adjacent to the inner surface of the can top thereby very substantially weakening the can top in the regions of the cuts so that the knockouts 34-34 may be removed with the sealing spirals 36-36 secured thereover on the can top. As in the form of spirals and finger tab illustrated in the embodiment of the invention of Figures 2 and 3, the flat spirals 36-36 of Figure 5 are interconnected by a finger pull link intermediate portion of wire 37. In this form of the invention the flat spirals are sealed onto the can top 32 overlying the knockouts and are removable by pulling the finger tab 37 to unwind the convolutions of the spirals 36-36 until they are of a diameter equal to or less than the diameter of the knockouts at which time the knockouts will pull out with the spirals thereby leaving open apertures in the top 32 of the can 30.

This form of the invention permits manufacture and utilization of a can with an unbroken surface on the interior of a can as in a conventional can thereby providing a still greater safety against contamination of any food products within the can or container since there is no possible breaking of the lacquer interior finish to the can before actually opening the apertures in the can by removal of the knockouts from the apertures.

In Figure 6 there is illustrated still another can 38 substantially identical to the cans 18, 22 and 30. In this figure, the entire can is shown in cross-section so that there is also seen the can bottom 39 roll sealed as at 40 to the can side walls 41. The top 42 of the can 38 is roll sealed as at 43 to the side walls 41 in the conventional manner.

In this form of the invention, however, the center of the can top 42 is apertured as at 44 and the metal is drawn into the can or spun or punched inwardly of the can. The inwardly drawn portion 45 of the can top 42 about the aperture 44 in the top serves as a guide for the upper free end 46 of a plastic or similar noncontaminating material straw 47 that may be preinserted in a beverage can. The straw 47 will have an axial length somewhat greater than the axial distance between the can top 42 and the can bottom 39 so that it will bend as at 48 but pop up straight and extend above the top surface of the can top 42 when the seal spiral 49 is removed.

The sealing spiral 49, as started hereinabove, is preferably of the form shown in Figure 1 and not only overlies the aperture region of the can top 42 but also holds the straw 47 in the can.

Removal of the spiral sealing unit 49, which is secured to the can top as are the other spirals described hereinabove in conjunction with Figures 1, 2, 3, 4 and 5, is effected by pulling the finger loop tab free end of the wire 50 to break the sealing means and unwind the convolutions until the spiral is of sufficiently small diameter to be free of the aperture region of the can top. As in the case of the spirals 15-15 of Figure 2, the spiral 49 of Figure 6 may be of a sufficiently small

diameter to lie within a boss region 51 in the center of the can top 42 for convenience of placement for radio frequency sealing and high production sealing and to provide the can with a small flat top as desired.

These and many other modifications, however, are clearly apparent and clearly fall within the spirit and scope of this invention.

Still additional forms of the instant invention are illustrated in Figures 7 and 8 for opening the entire top region of the can as by removal of the entire top of the can or a very large portion of the can top. These forms of the invention, and particularly the form of the invention of Figure 8, are adaptable for opening also smaller areas of the can top as will be explained hereinbelow in conjunction with Figure 8.

In Figure 7 there is shown a form of the invention for removal of the entire can top and in this embodiment the can side walls 52 of the can 53 terminate in an outwardly flanged upper end 54 with a slight upwardly extending lip 55 thereon at the outer end thereof. The can top 56 is provided with an upwardly stepped outwardly extending flange 57 at the outer periphery thereof with the step in the flange of the top 56 having a lesser diameter than the diameter of the lip 55 on the flange 54 of the side walls 52 in the can 53. This facilitates the utilization of an open center conically or flat spirally wound sealing unit in accordance with the principles of this invention. In the embodiment of Figure 7 spirally wound sealing unit 58 is shown as conically formed, but it is understood that the sealing unit may be flat or conical as desired. The sealing unit 58 is somewhat different than the sealing units utilized in the embodiments of the invention illustrated in Figures 1 through 6 in that it is open centered rather than fully closed and is so formed for this embodiment of the invention that it has an inner diameter substantially the same as that of the step in the flange 57 on the top cover 56 and so that it has an outside diameter substantially the same as that of the lip 55 on the flange 54 of the side walls 52. This permits extremely convenient assembly by merely resting the secured together and sealed convolutions on the flange 54 of the can side walls 52 and then resting the can top 56 on the spiral seal member 58 with the flanges and steps in the sealing member all interfitting for efficient, convenient and easy high speed production line sealing of the cans. A free end from one of the outer convolutions of the spirally formed wire will form a pull tab much the same as the pull tab finger ring of the spiral seal member illustrated in Figure 1 and illustrated again in Figure 6 so that a mere pulling of the pull tab and finger ring for the spiral wire seal of Figure 7 will unwind the outer convolution to remove the entire can top and seal from the can 53 of Figure 7.

A similar open center spiral wire seal member is utilized in the form of the instant invention illustrated in Figure 8 wherein the can 59 has side walls 60 sealed to the can top 61 in a conventional roll seal 62. In this form of the invention, however, the can top is apertured as at 63 with an inwardly stepped flange 64 about the periphery of the aperture 63. This stepped flange 64 is then operative to receive a cover plate 65 thereon covering the entire aperture 63. The cover plate 65 is then sealed to the can top 61 about the outer periphery of the cover 65 by an open center flat or conical, depending upon the slope or flatness of the can top center region, spirally wound sealing member 66 with the outer convolutions thereof sealed onto the can top 61 and the inner convolutions thereof sealed onto the cover 65. A pull tab or finger ring like the pull tab finger ring of the embodiments of the invention of Figures 1 and 6, formed on the free end extending from an outer convolution then provides an easy and convenient spiral unwinding and seal breaking means through the utilization of mere manual force so that unwinding the outer con-

volutions results in a breaking of the seal and sufficient unwinding permits readily convenient removal of the cover 65 and access to the contents of the can 59.

From the foregoing it will be readily seen that there are numerous modifications and variations that can be effected without departing from the true spirit and scope of the novel concepts of this invention and included within this invention. Such a modification might be the utilization of plastic or thermoplastic materials whereby soldering may be avoided and the spiral seal members may be sealed to the containers by the mere utilization of heat and/or pressure or through the utilization of special chemicals, etc., effecting the sealing in the desired manner. Therefore, I intend to cover all such modifications and variations as fall within the true spirit and scope of the novel concepts and principles of this invention.

I claim as my invention:

1. A container and sealing means therefor comprising, a container having side walls, a bottom peripherally sealed to an end of said side walls, and a metallic top peripherally sealed to an opposite end of said side walls, an aperture in said top, and a seal, said seal comprising an elongated wire wound in a flat spiral substantially in one plane, said seal secured to said top and covering said aperture, said seal being secured to said top and between adjacent convolutions thereof by a material of sufficiently low tensile strength to be broken manually.

2. A container and sealing means therefor comprising, a container having side walls, a bottom peripherally sealed to an end of said side walls, and a metallic top peripherally sealed to an opposite end of said side walls, an aperture in said top, and a spirally wound elongated wire seal, said seal wound in flat spiral substantially in one plane, said seal secured to said top and covering said aperture, said seal being secured to said top and between adjacent convolutions thereof by a material of sufficiently low tensile strength to be broken manually and sufficiently high tensile strength to withstand forces resulting from fluid pressure within the container.

3. A container and sealing means therefor comprising, a container having side walls, a bottom peripherally sealed to an end of said side walls, and a metallic top peripherally sealed to an opposite end of said side walls, a pair of apertures in said top, an elongated wire seal secured to said top and having a pair of spirally wound portions covering said apertures, each portion comprising convolutions wound substantially in one plane, said wire seal being secured to said top and between adjacent convolutions thereof by material of sufficiently low tensile strength to be broken manually.

4. A container and sealing means therefor comprising, a container having side walls, a bottom peripherally sealed to an end of said side walls, and a metallic top peripherally sealed to an opposite end of said side walls, a pair of apertures in said top, an elongated wire seal secured to said top and having a pair of spirally wound portions covering said apertures, each portion comprising convolutions wound substantially in one plane, said wire seal being secured to said top and between adjacent convolutions thereof by material of sufficiently low tensile strength to be broken manually, said wire having an intermediate portion thereof forming a pull tab whereby both of said spiral portions may be removed by manual force on said pull tab.

5. A container and sealing means therefor comprising, a container having side walls, a bottom peripherally sealed to an end of said side walls, and a metallic top peripherally sealed to an opposite end of said side walls, a pair of apertures in said top, an elongated wire seal secured to said top and having a pair of conically spirally wound portions covering said apertures, convolutions of said spiral portions wound about a fixed center and continually receding from it, said wire seal being secured to said top and between adjacent convolutions

thereof by a solder material of sufficiently low tensile strength to be broken manually.

6. A container and sealing means therefor comprising, a container having side walls, a bottom peripherally sealed to an end of said side walls, and a metallic top peripherally sealed to an opposite end of said side walls, a pair of apertures in said top, and elongated wire secured to said top and having a pair of flat spirally wound portions covering said apertures, the convolutions of said portions wound in one plane about a fixed center, said wire being sealed to said top and between adjacent convolutions thereof by a solder material of sufficiently low tensile strength to be broken manually.

7. A container and sealing means therefor comprising, a container having side walls, a bottom peripherally sealed to an end of said side walls, and a metallic top peripherally sealed to an opposite end of said side walls, an aperture in said top, a knockout filling said aperture, a spirally wound elongated wire secured to said top and to said knockout and covering said aperture, the convolutions of said spirally wound elongated wire arranged in one plane about a fixed center, said wire being sealed to said top and said knockout and between adjacent convolutions thereof by a material of sufficiently low tensile strength to be broken manually to permit removal of said wire by unwinding the same and removal of said knockout as said knockout is secured to said wire.

8. A container and sealing means therefor comprising, a container having side walls, a bottom peripherally sealed to an end of said side walls, and a metallic top peripherally sealed to an opposite end of said side walls, a pair of apertures in said top, an elongated wire secured to said top and having a pair of spirally wound portions covering said apertures, said portions comprising convolutions wound about a fixed center in one plane and receding from said center, said wire being sealed to said top and between adjacent convolutions thereof by a material of sufficiently low tensile strength to be broken manually, and knockouts filling said apertures and removable with said wire.

9. A container and sealing means therefor comprising, a container having side walls, a bottom peripherally sealed to an end of said side walls, and a metallic top peripherally sealed to an opposite end of said side walls, an aperture in said top, and a conically spirally wound elongated wire seal, the convolutions of said seal wound in juxtaposition and with the apex thereof extending downwardly within said aperture, said seal secured to said top and covering said aperture, said wire seal being secured to said top and between adjacent convolutions thereof by a material of sufficiently low tensile strength to be broken manually.

10. In combination with a container having side walls and top and bottom walls secured and sealed to said side walls, access means in the top wall of the container

for removal of contents of the container including an opening in said wall and a seal, said seal formed of a spirally wound elongated wire with its convolutions arranged substantially in one plane and wound about a fixed center and continually receding from it, said convolutions soldered together, said seal soldered to said top wall of said container, said solder permitting unwinding of the seal by manual force and effective to permit removal of at least a portion of the seal upon at least partial unwinding of the said wire.

11. In combination with a container having side walls and top and bottom walls secured and sealed to said side walls, access means for removal of the entire top of the container and the contents of the container including a spirally wound elongated wire seal arranged between said top and the upper portion of said side walls, the convolutions of said seal wound in juxtaposition and soldered together, said seal secured to said top and side walls of said container by solder permitting unwinding thereof by manual force and effective to permit removal of the entire top upon at least partial unwinding of the said wire.

12. In combination with a container having side walls and top and bottom walls secured and sealed to said side walls, access means for removal of contents of the container including an aperture in said top wall, a cover to overlie said aperture in said top wall, and a spirally wound elongated wire seal, the convolutions of said seal wound substantially in one plane in juxtaposition and soldered together, said seal secured to said top wall of said container and to said cover by means permitting unwinding thereof by manual force and effective to permit removal thereof and of said cover upon at least partial unwinding of said wire.

13. In combination with a container having side walls and top and bottom walls secured and sealed to said side walls, access means for removal of contents of the container including a plurality of apertures in said top wall, a spirally wound elongated wire seal having spirally wound convolutions thereof wound about a fixed center and receding from it, said convolutions secured together and to said top wall of said container and over said apertures respectively by solder permitting unwinding thereof by manual force and effective to permit removal of the spirally wound portions of said wire upon at least partial unwinding of said wire.
